UNITED STATES PATENT OFFICE.

HUBERT M. PERRY, OF CHICAGO, ILLINOIS, ASSIGNOR TO ALBERT G. WELCH, TRUSTEE
OF EDWIN S. WOODS, DECEASED.

ANTIFRICTION SIDE BEARING.

1,236,478.

Specification of Letters Patent. Patented Aug. 14, 1917.

Application filed May 25, 1917. Serial No. 170,827.

To all whom it may concern:

Be it known that I, HUBERT M. PERRY, a citizen of the United States, and a resident of Chicago, in the county of Cook and State of Illinois, have invented certain new and useful Improvements in Antifriction Side Bearings, and I do hereby declare that the following is a full, clear, and exact description thereof, reference being had to the accompanying drawings, and to the letters of reference marked thereon, which form a part of this specification.

This invention relates to improvements in antifriction side bearings and consists of the matters hereinafter described and more particularly pointed out in the appended claims.

The object of the invention is to provide an antifriction side bearing comprising but few parts so arranged that they will automatically adjust themselves to the shifting positions of the body and truck bolsters of a railway car, so that the transmitted load is at all times distributed equally to the antifriction element in the plane of its rotative axis.

Other objects together with the several advantages of my improved antifriction side bearing will more fully appear as I proceed with my specification.

In the drawings:

Figure 1 illustrates a transverse, sectional view through an antifriction side bearing embodying my invention, the plane of the section being indicated by the line 1--1 of Fig. 2.

Fig. 2 illustrates a top plan view of the same.

Fig. 3 illustrates a longitudinal section through the antifriction side bearing, the plane of the section being indicated by the line 3--3 of Fig. 2.

Fig. 4 illustrates a perspective view of a rocking member or shoe forming a part of my improved antifriction side bearing.

Fig. 5 is a view similar to that shown in Fig. 1, and illustrates a modified form of my improved antifriction side bearing.

Referring now in detail to that embodiment of the invention illustrated in the accompanying drawings and particularly in Figs. 1 to 4 inclusive:—10 indicates a casing and 11 indicates an antifriction roller con-

tained therein. The antifriction side bearing is specifically illustrated herein, as of the type which is adapted to be attached to the truck bolster of a railway car. 12 indicates said truck bolster and 13 indicates the associated body bolster. The bearing is adapted to transmit load from said body bolster to said truck bolster in a familiar manner. The truck bolster is illustrated in this instance as constructed to present a horizontal top face upon which the bearing rests.

The casing 10 is preferably made rectangular and somewhat elongated in plan and is open at its top and bottom. It has upright side and end walls 14, 15, respectively, and has at the bottom edges of said walls, 16 horizontal ears by means of which it is attached to the truck bolster 12. A strengthening or bracing rib 16^a connects each ear 16 with the associated side wall and ventilation openings 17 are provided in the bottom edge of each side wall between the ribs 16^a and the adjacent end walls 14. The bottom, inner edges of the end walls 14 are recessed to provide shoulders 18 (see Fig. 3) to receive and hold in place the marginal ends of a flat wear plate 19, which closes the open bottom of said casing when said casing is attached to the truck bolster.

Within the casing 10 and resting upon the wear plate 19, is a rocker 20 (see Fig. 4) which approximately fills said casing. Said rocker is capable of a limited, rocking movement and is made in the form of an open top, rectangular, comparatively shallow shell having a horizontal, bottom wall 21, upright side walls 22 and upright end walls 23 which are preferably made higher at their middle and thicker than said side walls 22. The bottom surface 24 of the horizontal wall 21 is curved or rounded throughout its greater length from end to end of the rocker, the end parts of the bottom surface of said horizontal wall being formed to provide transverse stop shoulders 25 for a purpose soon to appear. The said rounded surface 24 is preferably a cylindric surface described about an axis located in the transverse median plane of the rocker, preferably at a considerable distance above the top surface of the antifriction roller 11. The axis 105 of curvature of said cylindric surface 24 is

also located in a plane which extends at right angles to the surface on which the rocker bears.

The antifriction element or roller 11 is 5 journaled on a shaft 26 which in itself is non-rotatively mounted in suitable openings formed in the thickened end walls 23 of the rocker, a journal sleeve or bushing 27 being secured in said roller and bearing upon 10 said shaft. As shown the shaft 26 is cut away or flattened at one of its ends as at 28, the associated hole in one of the end walls of the rocker being formed to receive 15 said flattened end and hold said shaft against rotative movement. Ventilation openings 29 are provided in the bottom horizontal wall of the rocker which open into the interior of the casing 10, so that dust, dirt, or other foreign substances cannot 20 accumulate in the interior of said rocker.

On the outer face of each side wall of the rocker, at its middle and near its rounded, cylindric, bottom surface and in the plane of its transverse median axis, are 25 laterally extending studs 30 which project into downwardly opening, hollow, U-shaped housings provided for by bosses 31, made integral, as shown, with the side walls 15 of the casing. This structure just described 30 holds the rocker in alinement with the casing and prevents endwise, slipping movement of the rocker within the casing during its operation, but does not prevent the rocking movement thereof.

35 In Fig. 5 is shown a modified form of the invention, which is more particularly adapted for use in connection with a truck bolster having a bearing surface which is inclined to the horizontal instead of being arranged in a horizontal plane as before mentioned. In this instance, the truck bolster 12^a is shown as inclined and no wear plate 19 is used. The rocker 20 engages directly upon said body bolster. Under such circumstances, I preferably describe the cylindric bearing surface 24^a of the rocker 20 about an axis located in a plane above and extending at a right angle to the inclined bearing surface of the truck bolster 12^a, all 50 of the other parts of the bearing, as a whole, being substantially the same as before described and illustrated in Figs. 1 to 4 inclusive of the drawings.

It is apparent that when the load is 55 greater at one end of the antifriction element or roller 11, than it is at the other, the rocker will rock crosswise of the casing and automatically bring the antifriction element or roller 11 into such position as to 60 present the full line, intended contact thereof to the body bolster. This rocking movement of the rocker is limited by the engagement of the transverse stop shoulders 25 with the surface upon which the rocker has 65 rocking bearing.

The improved side bearing thus provides for the relative rocking or swaying movement of the body and truck bolsters in their vertical planes and eliminates unequal wear upon the roller 11.

The improved antifriction side bearing 70 comprises but few parts which may be made comparatively small in size, and yet withstand the weight or load imposed upon them in use. No springs or like devices, which 75 easily become broken or out of order, are used, and while there is sufficient flexibility between the parts to permit of the intended movement, the parts so co-act that rattling and other noises are eliminated.

80 While in describing my improved antifriction side bearing, I have referred to certain details of mechanical construction and arrangement of parts, I do not wish to be limited thereto except as may be pointed out 85 in the appended claims.

I claim as my invention:

1. An antifriction side bearing comprising a casing adapted for attachment to a truck bolster, a rocker having side members, 90 an antifriction roller rotatively mounted in said side members, said rocker having a cylindrical bottom with its axis arranged transversely of the axis of said roller, and means providing a flat seat for the cylindri- 95 cal bottom of said rocker.

2. An antifriction side bearing comprising a casing adapted for attachment to a truck bolster, a rocker consisting of a shell having side and end walls and a bottom wall, 100 an antifriction roller rotatively mounted in said side walls, the bottom wall of said rocker having a cylindrical surface with its axis arranged transversely of the axis of said roller and in a plane extending trans- 105 versely of said bolster and at right angles to the top plane thereof, and means providing a flat seat for the bottom surface of said rocker.

3. An antifriction side bearing comprising a casing adapted for attachment to a truck bolster, a rocker having side members, an antifriction roller rotatively mounted in said side members, said rocker having a cylindrical bottom with its axis arranged 115 transversely of the axis of said roller, means providing a flat seat for the cylindrical bottom of said rocker, and means at the ends of the bottom surface of the rocker to engage said flat seat and limiting the 120 rocking movement of said rocker.

4. An antifriction side bearing comprising a casing adapted for attachment to a truck bolster, a rocker having side members, 125 an antifriction roller rotatively mounted in said side members, said rocker having a cylindrical bottom with its axis arranged transversely of the axis of said roller, and means providing a flat seat for the cylindri- 130 cal bottom of said rocker, said means in-

cluding a plate protecting the top of said bolster and held thereon by said casing.

5. An antifriction side bearing comprising a casing adapted for attachment to a truck bolster, a rocker having side members, an antifriction roller rotatively mounted in said side members, said rocker having a cylindrical bottom surface the axis of which is arranged transversely of the axis 10 of said roller, and means providing a flat seat for the bottom of said rocker, said rocker and casing being provided with associated parts to lock said rocker to its seat but permitting its free rocking movement.

15 6. An antifriction bearing comprising a casing, means providing a flat bearing surface at the bottom of said casing, a rocker in said casing, said rocker having a longitudinally arranged cylindric bearing surface 20 adapted to rock on said flat bearing surface, shoulders at the ends of said curved bearing surface, limiting the rocking movement of said rocker, a shaft fixed in said rocker and extending transversely to said cylindric bearing surface, a roller having a bushing journaled on said shaft, and means on said 25 rocker between its ends adapted to coact

with fixed parts of the casing preventing endwise slipping or twisting movement of said rocker on said flat bearing surface.

30

7. An antifriction bearing comprising an open top casing, a plate confined in the bottom of said casing and providing a flat bearing surface, a rocker in said casing, said rocker having a longitudinally arranged, cylindric bearing surface adapted to rock on said flat bearing surface, shoulders at the ends of said cylindric bearing surface, limiting the rocking movement of said rocker, a shaft fixed in said rocker and extending transversely to said cylindric bearing surface, a roller having a bushing journaled on said shaft, and means on said rocker between its ends adapted to coact with fixed parts of the casing to prevent endwise slipping or twisting movement of said rocker on said plate.

35

In testimony, that I claim the foregoing as my invention I affix my signature in the presence of two witnesses, this 4th day of May A. D. 1917.
